UNITED STATES PATENT OFFICE

HEINRICH GUTTINGER, OF WETTINGEN, SWITZERLAND, ASSIGNOR TO AKTIENGESELLSCHAFT BROWN BOVERI & CIE., OF BADEN, SWITZERLAND, A JOINT STOCK COMPANY OF SWITZERLAND

ELECTRIC REGULATOR

Application filed March 13, 1930, Serial No. 435,416, and in Germany March 25, 1929.

This invention relates to improvements in electric regulating apparatus and, particularly, to electric regulators of the voltage or current-limiting type such as illustrated in my U. S. Letters Patent No. 1,003,600.

Such regulators may generally be divided into two systems, namely, a motive system and a regulating or resistance system. The motive or operating system may produce an over or under regulation of the machine to be controlled, which results in a quick, aperiodic regulating action. The motive system must be provided with a recall or returning device for reestablishing the former predetermined conditions after each operation of the motive system. Such recall device may consist of a damping arrangement for the motive system, together with a spring. Both the damping arrangement and the spring must be regulated according to the time constant of the machine to be controlled to produce the most favorable results in the control of such machine. The damping arrangement and the spring, should, therefore, both be adjustable to secure proper setting of the regulator. When the damping arrangement is of the magnetic retarded disc type, the position of the damping magnets may readily be varied to obtain any desired retarding effect, but it is possible to adjust the usual spiral spring only by trial and error which requires a large stock of springs and a great length of time, by persons skilled in the adjustment of such regulators, to secure the proper setting. The use of a helical spring was considered undesirable or impossible heretofore, for the reason that no arrangement was known by which such spring might be embodied in a regulator in such manner as to produce the necessary spring characteristics which would damp out periodic oscillation and reproduce the state of equilibrium to permit the desired over-regulation while preventing "hunting" and thereby minimizing the total time required for the regulating action.

It is, therefore, among the objects of the present invention to provide a recall device for an electric regulator of the type generally illustrated and described in U. S. Patent No.

1,003,600, which will permit accurate adjustment thereof in a minimum of time.

Another object of the invention is to provide a recall device for an electric regulator, in which the device is adjustable without disconnection of any of the portions thereof.

Another object of the present invention is to provide a recall device for an electric regulator, in which a helical spring is so arranged as to have substantially a constant torque and in which the spring need not be released or removed to permit adjustment of the regulator.

Objects and advantages, other than those above set forth, will be apparent from the following description, when read in connection with the annexed drawing which illustrates one embodiment of the present invention in front elevation.

Referring more particularly to the drawing by characters of reference, the reference numeral 1 indicates the shaft of a regulator on which is mounted a sleeve 2 rotatable about the shaft 1. A sector gear or sector 3 having a toothed portion is mounted on the sleeve 2 for rotation therewith and the sector gear engages a pinion 4 mounted on a shaft 6 on which is also mounted a disc 7. The disc 7 is arranged to rotate between the poles of a plurality of magnets, of which only the magnet 8 is shown, which magnets have a retarding effect on the disc as will be understood.

An arm 9 is keyed to the shaft 1 and has fastened thereto one end of a helical spring 11. The opposite end of the spring 11 is screw-threaded or provided with a screw-threaded stud passing through a bracket 12 extending from the sector gear 3 parallel to the shaft 1 and over the arm 9 when the device is in the predetermined equilibrium position. The spring is held in tensioned condition by adjusting nuts 13 arranged in engagement with the screw-threaded end or the stud on the end of the spring 11. Mere adjustment of the nuts 13 is sufficient to secure the most exact and fine adjustment of the spring under any desired conditions. The action of the entire recall device may thus be exactly adjusted, by change of posi-

tion of the magnets 8 and change of tension of the spring 11, without disturbing the relation of any of the parts or disassembling the regulator in any way. A regulator is thus provided in which the recall device follows the motive system with a certain time lag and the recall device acts to facilitate return of the motive system to the equilibrium position, without any undesirable oscillation occurring in the regulator.

10 Although but one embodiment of the present invention has been illustrated and described, it will be apparent that changes may be made therein without departing from the spirit of the invention or from the scope of the appended claims.

15 The invention claimed is:

1. An electric regulating apparatus having a shaft, a recall device comprising a sector gear rotatably mounted on the shaft of the regulating apparatus, a magnetic damping device engaging said sector gear, an arm mounted on the shaft of the regulating apparatus and rotatable therewith, and a spring connecting said sector gear with said arm.

20 2. An electric regulating apparatus having a shaft, a recall device comprising a sector gear rotatably mounted on the shaft of the regulating apparatus, a disc actuated by said sector gear, means for magnetically retarding the rotation of said disc under the action of said sector gear, an arm mounted on the shaft of the regulating apparatus and rotatable therewith, and a helical spring adjustably connecting said sector gear with said arm.

25 In testimony whereof I have hereunto subscribed my name this 3rd day of March, A. D. 1930.

30 40 HEINRICH GUTTINGER.
